(57) **CLAIM**

The ornamental design for an LED lighting fixture, as shown and described.

DESCRIPTION

FIG. 1 is a front three-dimensional view of the LED lighting fixture;

FIG. 2 is a front elevational view of the LED lighting fixture;

FIG. 3 is a rear elevational view of the LED lighting fixture;

FIG. 4 is a side elevational view of the LED lighting fixture;

FIG. 5 is another side elevational view of the LED lighting fixture;

FIG. 6 is a top plan view of the LED lighting fixture; and,
FIG. 7 is a bottom plan view of the LED lighting fixture.
The broken lines depict portions of the LED lighting fixture
in which the design is embodied and form no part of the
claimed design.
